AUTOMATIC VISUAL REFERENCE SYSTEM

Francis W. Sammons, St. Albans, N. Y.

Application May 27, 1939, Serial No. 276,115

14 Claims. (Cl 129—16)

This invention relates to new and useful improvements in an automatic visual reference system.

The invention has for an object the construction of a system as mentioned which is characterized by a cabinet, a drawer slidably mounted therein, and a novel arrangement for individually displaying each card in the cabinet as the drawer is pulled open.

10 Still further the invention contemplates an arrangement which will automatically reverse itself and act to display each card in reverse order when the drawer is closed.

Still further the invention proposes the use of 15 friction wheels arranged to engage the edges of the cards in a novel fashion and to operate to move the cards so that they may be individually seen.

Another object of this invention resides in the 20 provision of a driving means for the friction wheels arranged to be operatively connected with the drawer to operate in one direction when the drawer is pulled outwards and in the other direction when the drawer is pushed inwards. In 25 this way it is proposed to cause the friction wheels to operate in one or the other direction for facilitating selectively moving the cards forwards or rearwards.

Still further the invention proposes the construction of a device as mentioned which is 30 simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

40 In the accompanying drawings forming a material part of this disclosure—

Fig. 1 is a horizontal sectional view of a filing cabinet equipped in accordance with this invention.

45 Fig. 2 is a transverse vertical sectional view of the front portion of Fig. 1.

Fig. 3 is a fragmentary longitudinal sectional view taken on the line 3—3 of Fig. 2.

Fig. 4 is a fragmentary sectional view taken on 50 the line 4—4 of Fig. 1.

Fig. 5 is a fragmentary view similar to the right hand portion of Fig. 1 but illustrating the parts in a different position.

Fig. 6 is a fragmentary horizontal sectional view 55 taken on the line 6—6 of Fig. 2.

Fig. 7 is a fragmentary vertical sectional view taken on the line 7—7 of Fig. 2.

Fig. 8 is a fragmentary vertical sectional view taken on the line 8—8 of Fig. 2.

The automatic visual reference system in accordance with this invention includes a cabinet 10. A drawer 11 is slidably mounted in the cabinet and holds a plurality of cards 13 in a close stacked condition with each card in a vertical position in the drawer. The drawer 11 is adapted 10 to be pulled out and pushed in, when desired. It may be slidably supported in any desired manner. In the drawings it is shown with track elements 14 mounted upon the bottom of the drawer and engaging complementary track elements 15 mounted upon the cabinet 10.

A pair of brackets 16 is pivotally mounted in the cabinet 10 near the front of the drawer 11 when the latter is in its closed position. This pair of brackets is arranged so that there is one 20 bracket on each side of the drawer. Each bracket 16 indirectly supports a friction wheel 17. Each wheel 17 extends rearwards and each engages in edgewise contact with the edges of the front cards 13 located immediately to the rear of the friction wheels. Each friction wheel is resiliently supported.

More specifically each friction wheel 17 includes a base portion 17^a with a covering of friction material 17^b such as rubber material. Each 30 friction wheel has a beveled edge 17^c which engages the edges of the cards 13. Each friction wheel 17 is fixedly mounted on a square shaft 18, which slidably engages through a similar opening in a bushing 19 mounted in the front end of a 35 shaft 20. A head element 21 is fixed on the inner end of each shaft 18, and expansion springs 22 are used in each shaft 20, and act against the heads 21 for resiliently urging the shafts 18 into extended positions.

40 A bevel gear 23 is mounted upon each shaft 20. Each shaft 20 is rotatively but non-slidably supported in an arm 16^a of the bracket 16. Each bevel gear 23 meshes with a bevel gear 24 fixedly held on a shaft 25 rotatively mounted in a vertical position through the bracket 16. Each shaft 25 is also mounted through a bearing 26 on a stationary block 27 fixedly mounted in the cabinet. The arrangement is such that each bracket 16 is free to turn on the shaft 25. A roller 28 50 is mounted on an outer portion of each bracket 16 and engages against the top of the block 27 for assisting in rotatably supporting the bracket.

A means is provided for driving the friction wheel 17 forwards and rearwards and this means 55

is operatively connected with the drawer 11. This means includes a bevel gear 29 on the lower end of each shaft 25 meshing with a bevel gear 30 mounted upon a shaft 31 which is rotatively supported in a horizontal position. This shaft 31 extends transversely of the drawer 11 and through slots 32 formed in the bottom wall of the drawer. Gears 33 are mounted upon the shaft 31 and mesh with racks 34 mounted upon the drawer 11. 10 The arrangement is such that when the drawer 11 is pulled out the racks 34 will turn the gears 33 and so the shaft 31. This rotation is transmitted indirectly to rotate the friction wheels 17.

A means is provided for pivoting each bracket 16 when the drawer is pushed inwards to direct the friction wheels forwards and in edge contact with the edges of the cards to the front, so that the cards are moved individually rearwards as the drawer is pushed closed, and the friction 20 wheels turn rearwards. This pivoting means includes a rod 35 attached on each bracket 16 and extending downwards and engaging in between a pair of stops 36 and 37 which are stationarily mounted on the cabinet 10.

25 These rods 35 limit pivoting of the bracket 16 around the shaft 25 through a certain predetermined distance. A spring 38 is attached to each rod 35 and to the block 27 at points so as to hold the bracket 16 pivoted in one direction with the finger engaging the stop 37, or if the bracket 16 is pivoted in the other direction so that the finger 35 engages the stop 36, the spring 38 will hold the bracket in this latter position. The spring 38 is arranged so as to pass the dead center of pivoting of the bracket 16 and it is for this reason that it holds the bracket in one or the other direction.

A wheel 39 is provided for each rod 35, and is fixedly mounted on the shaft 31. These wheels have resilient radial projections 39^a which strike 40 against projections 40 on the rods 35. The arrangement is such that when the shaft 31 turns in one direction the resilient fingers 39 will strike the projections 40 and move the rods 35 so that the brackets 16 are in one or the other positions. 45 When the shaft 31 rotates in reverse direction the resilient fingers 39 will strike the projections 40 to pivot the bracket 16 into the other direction. The arrangement is such that when the brackets 16 are in one or the other positions further 50 rotations of the wheels 39 in the same direction will result merely in the resilient fingers 39^a flexibly passing the projections 40. This is so because the brackets 16 cannot pivot further in this particular direction since the rods 35 are striking 55 the stops 36 or 37. However when the shaft 31 is reversed it will cause the pivoting of the brackets 16 as mentioned.

A roller 41 is mounted centrally on the shaft 31 and projects up through the bottom wall of the drawer 11 through a slot 42. This roller 41 engages the bottom edges of the cards 13 which are between the friction wheels 17.

The operation of the device is as follows:

When the drawer is pulled out the friction 60 wheels 17 will engage the end edges of the cards 13 which are between the friction wheels, and bow them slightly forwards as illustrated in Fig. 1. The friction wheels 17 will be driven in one direction by the transmission which is connected 65 with the drawer 11. This transmission includes the racks 34 engaging the gears 33, and the gear transmission system including the bevel gears 23. This rotation of the friction wheels 17 will cause 70 the cards 13 to individually move forwards one at a time. The drawer may be slowly pulled open,

and the cards watched and so individually inspected without actually touching of the cards manually.

If the operator wishes to see some of the cards which have already passed, it is merely necessary 5 that the drawer 11 be pushed slightly inwards. This will cause the racks 34 to drive the gears 33 in the opposite direction. The transmission is now working in reverse and the friction wheels 17 are now being turned in the opposite direction. 10 Simultaneously, with the first impulse of inward motion of the drawer 11, the wheels 39 acting in conjunction with the projections 40 will pivot the rods 35 to their other positions which accordingly 15 pivots the brackets 16. This latter mentioned position is illustrated in Fig. 5. In this new position the friction wheels 17 are now engaging the edges of the cards to the front of them and these cards will be pushed backwards one at a time 20 so that they may be individually inspected.

The roller 41 assists in moving the cards forwards or rearwards. This roller 41 which is of friction material engages the bottom edges of the cards which are being operated upon by the friction wheels 17 throwing them forwards or rearwards 25 depending upon the direction of motion of the drawer.

While I have illustrated and described the preferred embodiments of my invention, it is to be 30 understood that I do not limit myself to the precise constructions herein disclosed and the right is reserved to all changes and modifications coming within the scope of the invention as defined in the appended claims.

Having thus described my invention, what I 35 claim as new and desire to secure by United States Letters Patent is:

1. An automatic visual reference system, comprising a cabinet, a drawer slidably mounted therein for holding cards or the like in a close 40 stacked position with each of the cards in a vertical position, a pair of brackets pivotally mounted on vertical axes in said cabinet near the front of said drawer, and one bracket being on each side of said drawer, a friction wheel rotatively supported on each bracket and extending rearwardly and in edgewise contact with the end edges of the front cards in said drawer to the rear of the friction wheels, means for driving said friction wheels forwards or rearwards and operatively connected with said drawer for moving said cards individually forwards as the drawer is pulled open and the friction wheels turn forwards so that the cards may be individually inspected, and means 50 for pivoting said brackets when the drawer is pushed inwards and in edgewise contact with the edges of the cards to the front so that the cards are moved individually rearwards as the drawer is pushed closed and the friction wheels turn rearwards.

2. An automatic visual reference system, comprising a cabinet, a drawer slidably mounted therein for holding cards or the like in a close 65 stacked position with each of the cards in a vertical position, a pair of brackets pivotally mounted on vertical axes in said cabinet near the front of said drawer, and one bracket being on each side of said drawer, a friction wheel rotatively supported on each bracket and extending rearwardly 70 and in edgewise contact with the end edges of the front cards in said drawer to the rear of the friction wheels, means for driving said friction wheels forwards or rearwards and operatively connected with said drawer for moving said cards 75

- individually forwards as the drawer is pulled open and the friction wheels turn forwards so that the cards may be individually inspected, and means for pivoting said brackets when the drawer is pushed inwards and in edgewise contact with the edges of the cards to the front so that the cards are moved individually rearwards as the drawer is pushed closed and the friction wheels turn rearwards, said friction wheels being resiliently urged against the edges of the cards.
3. An automatic visual reference system, comprising a cabinet, a drawer slidably mounted therein for holding cards or the like in a close stacked position with each of the cards in a vertical position, a pair of brackets pivotally mounted on vertical axes in said cabinet near the front of said drawer, and one bracket being on each side of said drawer, a friction wheel rotatively supported on each bracket and extending rearwardly and in edgewise contact with the end edges of the front cards in said drawer to the rear of the friction wheels, means for driving said friction wheels forwards or rearwards and operatively connected with said drawer for moving said cards individually forwards as the drawer is pulled open and the friction wheels turn forwards so that the cards may be individually inspected, and means for pivoting said brackets when the drawer is pushed inwards and in edgewise contact with the edges of the cards to the front so that the cards are moved individually rearwards as the drawer is pushed closed and the friction wheels turn rearwards, said friction wheels being resiliently urged against the edges of the cards, each friction wheel being associated with telescopically engaging shafts, and expansion springs connected between sections of these shafts and accomplishing the resilient urging of said friction wheels.
4. An automatic visual reference system, comprising a cabinet, a drawer slidably mounted therein for holding cards or the like in a close stacked position with each of the cards in a vertical position, a pair of brackets pivotally mounted on vertical axes in said cabinet near the front of said drawer, and one bracket being on each side of said drawer, a friction wheel rotatively supported on each bracket and extending rearwardly and in edgewise contact with the end edges of the front cards in said drawer to the rear of the friction wheels, means for driving said friction wheels forwards or rearwards and operatively connected with said drawer for moving said cards individually forwards as the drawer is pulled open and the friction wheels turn forwards, so that the cards may be individually inspected, and means for pivoting said brackets when the drawer is pushed inwards and in edgewise contact with the edges of the cards to the front so that the cards are moved individually rearwards as the drawer is pushed closed and the friction wheels turn rearwards, said means for driving the friction wheels including a transmission system having a shaft rotatively supported and provided with gears, and racks mounted upon said drawer and engaging said gears for turning the gears in one or the other direction as the drawer is moved.
5. An automatic visual reference system, comprising a cabinet, a drawer slidably mounted therein for holding cards or the like in a close stacked position with each of the cards in a vertical position, a pair of brackets pivotally mounted on vertical axes in said cabinet near the front of said drawer, and one bracket being on each side of said drawer, a friction wheel rotatively supported on each bracket and extending rearwardly and in edgewise contact with the end edges of the front cards in said drawer to the rear of the friction wheels, means for driving said friction wheels forwards or rearwards and operatively connected with said drawer for moving said cards individually forwards as the drawer is pulled open and the friction wheels turn forwards so that the cards may be individually inspected, means for pivoting said brackets when the drawer is pushed inwards and in edgewise contact with the edges of the cards to the front so that the cards are moved individually rearwards as the drawer is pushed closed and the friction wheels turn rearwards, rods attached on the brackets and movable between stops to limit the pivoting of said brackets, and springs connected with said rods and acting across the dead center of pivoting of said brackets to hold the brackets in one or the other position.
6. An automatic visual reference system, comprising a cabinet, a drawer slidably mounted therein for holding cards or the like in a close stacked position with each of the cards in a vertical position, a pair of brackets pivotally mounted on vertical axes in said cabinet near the front of said drawer, and one bracket being on each side of said drawer, a friction wheel rotatively supported on each bracket and extending rearwardly and in edgewise contact with the end edges of the front cards in said drawer to the rear of the friction wheels, means for driving said friction wheels forwards or rearwards and operatively connected with said drawer for moving said cards individually forwards as the drawer is pulled open and the friction wheels turn forwards so that the cards may be individually inspected, means for pivoting said brackets when the drawer is pushed inwards and in edgewise contact with the edges of the cards to the front so that the cards are moved individually rearwards as the drawer is pushed closed and the friction wheels turn rearwards, rods attached on the brackets and movable between stops to limit the pivoting of said brackets, and springs connected with said rods and acting across the dead center of pivoting of said brackets to hold the brackets in one or the other position.
7. An automatic visual reference system, comprising a cabinet, a drawer slidably mounted therein for holding cards or the like in a close stacked position with each of the cards in a vertical position, a pair of brackets pivotally mounted on vertical axes in said cabinet near the front of said drawer, and one bracket being on each side of said drawer, a friction wheel rotatively supported on each bracket and extending rearwardly and in edgewise contact with the end edges of the front cards in said drawer to the rear of the friction wheels, means for driving said friction wheels forwards or rearwards and operatively connected with said drawer for moving said cards individually forwards as the drawer is pulled open and the friction wheels turn forwards so that the cards may be individually inspected, means for pivoting said brackets when the drawer is pushed inwards and in edgewise contact with the edges of the cards to the front so that the cards are moved individually rearwards as the drawer is pushed closed and the friction wheels turn rearwards, rods attached on the brackets and movable between stops to limit the pivoting of said brackets, springs connected with said rods and acting across the dead center of pivoting of said brackets to hold the brackets in one or the other positions, and wheels hav-

ing flexible fingers engaging projections on said rods for flexing past the projections or for causing the brackets to pivot depending upon the direction of rotation of said wheels.

5. 8. An automatic visual reference system, comprising a cabinet, a drawer slidably mounted therein for holding cards or the like in a close stacked position with each of the cards in a vertical position, a pair of brackets pivotally mounted on vertical axes in said cabinet near the front of said drawer, and one bracket being on each side of said drawer, a friction wheel rotatively supported on each bracket and extending rearwardly and in edgewise contact with the end edges of the front cards in said drawer to the rear of the friction wheels, means for driving said friction wheels forwards or rearwards and operatively connected with said drawer for moving said cards individually forwards as the drawer is pulled open and the friction wheels turn forwards so that the cards may be individually inspected, and means for pivoting said brackets when the drawer is pushed inwards and in edgewise contact with the edges of the cards to the front so that the cards are moved individually rearwards as the drawer is pushed closed and the friction wheels turn rearwards, rods attached on the brackets and movable between stops to limit the pivoting of said brackets, springs connected with said rods and acting across the dead center of pivoting of said brackets to hold the brackets in one or the other positions, and wheels having flexible fingers engaging projections on said rods for flexing past the projections or for causing the brackets to pivot depending upon the direction of rotation of said wheels, said wheels being mounted on a shaft having gears meshing with racks mounted on said drawer.
40. 9. An automatic visual reference system, comprising a cabinet, a drawer slidably mounted therein for holding cards or the like in a close stacked position with each of the cards in a vertical position, a pair of brackets pivotally mounted on vertical axes in said cabinet near the front of said drawer, and one bracket being on each side of said drawer, a friction wheel rotatively supported on each bracket and extending rearwardly and in edgewise contact with the end edges of the front cards in said drawer to the rear of the friction wheels, means for driving said friction wheels forwards or rearwards and operatively connected with said drawer for moving said cards individually forwards as the drawer is pulled open and the friction wheels turn forwards so that the cards may be individually inspected, and means for pivoting said brackets when the drawer is pushed inwards and in edgewise contact with the edges of the cards to the front so that the cards are moved individually rearwards as the drawer is pushed closed and the friction wheels turn rearwards, a shaft for each of said friction wheels formed of separate sections telescopically engaging each other, said friction wheels being mounted on one of said sections and the other of said sections being rotatively but non-slidably supported on said brackets, and resilient means acting between said sections for urging said friction wheels resiliently against the card edges.
70. 10. An automatic visual reference system, comprising a cabinet, a drawer slidably mounted therein for holding cards or the like in a close stacked position with each of the cards in a vertical position, a pair of brackets pivotally mounted

ed on vertical axes in said cabinet near the front of said drawer, and one bracket being on each side of said drawer, a friction wheel rotatively supported on each bracket and extending rearwardly and in edgewise contact with the end edges of the front cards in said drawer to the rear of the friction wheels, means for driving said friction wheels forwards or rearwards and operatively connected with said drawer for moving said cards individually forwards as the drawer is pulled open and the friction wheels turn forwards so that the cards may be individually inspected, and means for pivoting said brackets when the drawer is pushed inwards and in edgewise contact with the edges of the cards to the front so that the cards are moved individually rearwards as the drawer is pushed closed and the friction wheels turn rearwards, means for holding said brackets in one direction or the direction past dead center, wheels with resilient fingers to urge the brackets in one direction past dead center when turned in one direction and in the other direction past dead center when turned in the other direction, and means for turning said wheels in one direction when the drawer is pulled out and in the other when the drawer is pushed in.

11. An automatic visual reference system, comprising a cabinet, a drawer slidably mounted therein for holding cards or the like in a close stacked position with each of the cards in a vertical position, a pair of brackets pivotally mounted on vertical axes in said cabinet near the front of said drawer, and one bracket being on each side of said drawer, a friction wheel rotatively supported on each bracket and extending rearwardly and in edgewise contact with the end edges of the front cards in said drawer to the rear of the friction wheels, means for driving said friction wheels forwards or rearwards and operatively connected with said drawer for moving said cards individually forwards as the drawer is pulled open and the friction wheels turn forwards so that the cards may be individually inspected, means for pivoting said brackets when the drawer is pushed inwards and in edgewise contact with the edges of the cards to the front so that the cards are moved individually rearwards as the drawer is pushed closed and the friction wheels turn rearwards, a friction roller transversely in the bottom of said drawer in line with said friction wheels, and means for driving said friction roller in one direction when the drawer is pulled out and in the other direction when pushed in to assist in moving said cards.

12. An automatic visual reference system, comprising a cabinet, a drawer slidably mounted therein for holding cards or the like in a close stacked position with each of the cards in a vertical position, a pair of brackets pivotally mounted on vertical axes in said cabinet near the front of said drawer, and one bracket being on each side of said drawer, a friction wheel rotatively supported on each bracket and extending rearwardly and in edgewise contact with the end edges of the front cards in said drawer to the rear of the friction wheels, means for driving said friction wheels forwards or rearwards and operatively connected with said drawer for moving said cards individually forwards as the drawer is pulled open and the friction wheels turn forwards so that the cards may be individually inspected, means for pivoting said brackets when the drawer is pushed inwards and in edgewise contact with the edges of the cards to the front

so that the cards are moved individually rearwards as the drawer is pushed closed and the friction wheels turn rearwards, a friction roller transversely in the bottom of said drawer in line with said friction wheels, and means for driving said friction roller in one direction when the drawer is pulled out and in the other direction when pushed in to assist in moving said cards, including a shaft supporting said friction roller and provided with gears meshing with racks mounted upon said drawer, said shaft being rotatively supported and relatively stationary in relation to said cabinet.

13. An automatic visual reference system, comprising a cabinet, a drawer slidably mounted therein for holding cards in a close stacked position with each of the cards in a vertical position, a pair of brackets mounted in said cabinet near the front of said drawer and arranged one on each side of said drawer, a friction wheel rotatively supported on each bracket and extending rearwardly and in edgewise contact with the end edges of the front cards in said drawer to the rear of the friction wheels, and means connected with said drawer for driving said friction wheels forwards when said drawer is pulled outwards and rearwards when said drawer is pushed inwards, so that when said drawer is pulled outwards and said friction wheels rotate forwards said cards will be moved individually forwards to expose their front faces to inspection after which

the cards will be stacked in the front of the drawer.

14. An automatic visual reference system, comprising a cabinet, a drawer slidably mounted therein for holding cards in a close stacked position with each of the cards in a vertical position, a pair of brackets mounted in said cabinet near the front of said drawer and arranged one on each side of said drawer, a friction wheel rotatively supported on each bracket and extending rearwardly and in edgewise contact with the end edges of the front cards in said drawer to the rear of the friction wheels, and means connected with said drawer for driving said friction wheels forwards when said drawer is pulled outwards and rearwards when said drawer is pushed inwards, so that when said drawer is pulled outwards and said friction wheels rotate forwards said cards will be moved individually forwards to expose their front faces to inspection after which the cards will be stacked in the front of the drawer, said brackets being pivotally mounted on vertical axes, and means for pivoting said brackets at the start of the inward motion of said drawer to cause said friction wheels to be brought into edgewise contact with the cards located in the front of said drawer to cause the cards to be individually returned to their starting position as the friction wheels rotate rearwards while the drawer is being pushed inwards. 30

FRANCIS W. SAMMONS.
